(57) **CLAIM**

The ornamental design for a digital signage for an automatic teller machine, as shown and described.

DESCRIPTION

FIG. 1 is a front perspective view of the first embodiment of a digital signage for an automatic teller machine shown in an environment of use, showing my new design;

FIG. 2 is a front perspective view of the digital signage for an automatic teller machine of FIG. 1, isolated for clarity of disclosure;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2;

FIG. 8 is a bottom plan view of FIG. 2;

FIG. 9 is a front perspective view of the second embodiment of a digital signage for an automatic teller machine shown in an environment of use;

FIG. 10 is a front perspective view of the digital signage for an automatic teller machine of FIG. 9, isolated for clarity of disclosure;

FIG. 11 is a front elevational view of FIG. 10;

FIG. 12 is a rear elevational view of FIG. 10;

FIG. 13 is a left-side elevational view of FIG. 10;

FIG. 14 is a right-side elevational view of FIG. 10;

FIG. 15 is a top plan view of FIG. 10; and,

FIG. 16 is a bottom plan view of FIG. 10.

The broken lines depicting an automatic teller machine in FIGS. 1 and 9 show environmental matter that forms no part of the claimed design. The remaining broken lines in the figures depict portions of the digital signage for an automatic teller machine that form no part of the claimed design.
